UNITED STATES PATENT OFFICE

LESTER S. GUNDERMAN, OF PITTSBURGH, PENNSYLVANIA

SAFETY DEVICE FOR CLOTHES WRINGERS

Application filed October 16, 1929. Serial No. 399,893.

This invention relates to a safety device for clothes wringers and like and relates particularly to a feeding means therefor whereby articles of clothing can be passed through the wringer without danger to the operator and without any necessity for the operator bringing his hands into contact with the rolls.

The invention has for its principal object a feeding device having a movable feed plate mounted in front of and slightly below the front edge of the standard guard when in an inoperative position so that the clothing can readily slide over the feeder when clothes are being run through the press roll from the opposite side thereof. According to the present invention, it is proposed to provide a feeder which will not interfere with the clothes being run through the wringer from either front or back of the wringer and it never needs to be removed from one side of the wringer to the opposite side thereof when required for use.

Wringer, from the beginning, have been equipped with a guard in the front and back in relation thereto when standing in front of the press rolls. These guards are to prevent clothes when being run through the press rolls from becoming entangled with the rolls and being damaged. These guards extend outward and downward to guide the clothes away from press rolls. In my present invention I install a feed bar on the front and back of the wringer. The feed bar is associated with the guards so that clothes slide over the guard and feeder when leaving the press rolls, making it unnecessary to remove any feeder when using the wringer in either direction as herein above related.

This invention may be readily understood by reference to the accompanying drawings which illustrate one embodiment of my invention, and in which:

Figure 1 is a front view of a wringer and my invention applied thereon.

Figure 2 is an end view of the wringer and the relation of the feeder thereon.

Figure 3 is a part section view on line A—A in Fig. 2, and for convenience I have shown a feeder mounted on one side of the wringer only.

Figure 4 is an enlarged section taken on line B—B in Fig. 1 and shows the feed plate in an inoperative position.

Figure 5 is an enlarged section taken on line B—B in Fig. 1 and shows position of feed bar when in an effective position as when feeding clothing to the press rolls.

In a more particular description of the parts, 7 designates the usual metal wringer frame, 8 and 9 designate the usual wringer rolls, which are driven from one end in a well known manner, 10 designates the general type of guard which is used and is pivotally mounted at 11 to the frame 7.

Thus far the elements referred to embody well known parts of a power driven wringer.

My improved construction of feeding device comprises members 12a and 12b which may be a separate part mounted on the frame 7 or may be an integral of the wringer as shown in the drawings. Extending across the distance between the projections 12a is a bell crank 13 which has its bearings 14 in the projections 12a and its ends extending outward forming handles 15. A second bell crank 16 extends across the distance between the projection 12a and has its bearings 17 on the projections 12a below bearings 14. Also extending across between the members 12a is a feed plate 18 having yokes 19 formed on the lower inner edge of said feed plate 18. The bell crank 16 passes through the yokes 19 and is so mounted that the plate is loosely connected with the said bell crank 13 at 20. To retain the bell cranks in their journal bearings on the projections 12a and 12b is a strip of metal 23 held in position by screws 24 on projections 12a and 12b.

When the operating handles 15 are raised

from the position as shown in Figure 5 the feed plate 18 is raised through a corresponding arc and the plate is guided in its movement through this arc by the bell cranks 13 5 and 16. By reason of the yoke 19 being reasonably loose on the bell crank 16 the plate 18 has considerable freedom of movement transversely relatively to the bell crank 16. In order to resiliently urge the plate 18 out- 10 wardly away from the bell crank 16 flat springs 21 (shown only in Figure 4) are pro- vided, one end of each being secured to plate 18 by rivets and the loose end thereof bearing against the bell crank 16 holding the surface 15 of the plate 18 upwardly away from the bell crank 16, thereby tending to urge the uppermost or forward end of the plate 18 down- ward. The forward edge of the plate 18 can yield upwardly when it comes in contact with the lower roll. If the clothes are being fed 20 through the wringer, the edge of the plate 18 may be raised an amount equal to the thickness of the clothes so that the clothes will be resiliently held against the upper surface of 25 the lower roll and drawn by the movement of this roll in between the two rolls.

The feed bar 18 is so mounted that the upper longitudinal edge is free to bring clothing in contact with the press rolls. The oppo- 30 site edge 22, being curved in a circular manner, prevents clothing from catching thereon and being torn or injured when being drawn through the press rolls. The curved edge 22 also facilitates the backward movement of 35 the feed plate 18 after the clothes have been caught between the bits of the rolls, as the clothes are drawn up over the edge 22 when being run through the press rolls.

When the feed plate is in its inoperative 40 position it lies in front of and slightly below the wringer guard and in front of the feed plate, being set at a lower plane than the feeding edge or receding downward away from the rolls so that when clothes are run 45 through the press rolls they will continue to slide down this plane with the least resistance possible.

In use the device is applied on each side 50 of the wringer and the feed plates are in the retractive position as shown in Figure 2. A portion of clothing is let fall on the guard 10, the handles 15 are raised and the forward edge of the feed plate 18 carries the portion 55 of clothing against the upper surface of the lower roll. As soon as the clothing is gripped by the press rolls the handles may be released and the feed bar is brought back to an in- 60 effective position in which position it does not interfere with the operation of the press rolls after the clothes have passed through the press rolls from either side thereof.

With such a feeder as described and having an extended way for the clothes to slide over there is no occasion for the operator to bring 65 his fingers in contact with the press rolls.

It is to be understood that this form of my invention herein shown and described is to be taken as a preferred design of the same, and that various minor changes in the shape and arrangement of the parts may be resorted to 70 without departing from the spirit of the invention or scope of the claims.

Having described my invention what I claim as new and desire to secure by Letters Patent is:

1. An attachment for a clothes wringer having a stationary feed plate thereon, including a movable feed plate normally positioned to afford a continuation of the stationary feed plate and the inner edge thereof being movable from such position to a raised feeding position. 75

2. An attachment for a clothes wringer having a stationary feed plate extending across between a wringer frame, including a feed plate extending transversely across the wringer and being normally positioned to afford a continuation of said feed plate and being movable from such a position to a raised feeding position. 80

3. A feeding device for wringers includ- 90 ing a stationary feed plate thereon, comprising a pair of bell cranks journaled on the wringer frame one above the other, a second feed plate extending transversely across the wringer and having the lower curved edge 95 thereof loosely hinged to the center of the lower bell crank, the upward ends of said feed plate being loosely hinged to the upper bell crank and the upper edge being arranged 100 in front of the stationary feed plate and at an outward and downward inclination there- to said bell cranks providing means to move the said second feed plate into and out of op- erative position. 105

4. A feeding device for clothes wringer including a stationary feed plate thereon, comprising supporting brackets mounted thereon, a pair of bell cranks loosely sup- 110 ported on the said brackets, an angularly ar- ranged feed plate loosely mounted on the bell cranks in front of the said stationary feed plate and being movable from such a position to a raised feeding position.

5. A feeding device for wringers includ- 115 ing a stationary guard thereon, comprising supporting members mounted on the wringer frame, a pair of bell cranks journaled on the supporting members, an angularly arranged feed plate having its lower curved edge re- 120 siliently held on the lower bell crank, the ends of said feed plate being loosely hinged on the upper bell crank, said feed plate being normally positioned to afford a continuation of the said stationary feed plate and being movable from such a position to a raised feeding position. 125

6. A feeding device for clothes wringers including guards thereon, a pair of bell cranks loosely mounted on the wringer 130

frame, an angularly arranged feed plate having the lower curved edge thereof resiliently held on the center of the lower bell crank the upper ends of the feed plate being loosely
5 hinged to the upper bell crank, and being normally positioned to afford a continuation of the guards and being movable from such a position to a raised feeding position.

10 In testimony whereof I have affixed my signature.

LESTER S. GUNDERMAN.
